UNITED STATES PATENT OFFICE.

CHARLES PERILLAT, OF BOSTON, MASSACHUSETTS, ASSIGNOR TO KITSON HYDROCARBON HEATING AND INCANDESCENT LIGHTING COMPANY, OF PHILADELPHIA, PENNSYLVANIA, A CORPORATION OF WEST VIRGINIA.

HYDROCARBON STREET-LAMP.

SPECIFICATION forming part of Letters Patent No. 739,711, dated September 22, 1903.

Application filed September 20, 1901. Serial No. 75,753. (No model.)

To all whom it may concern:

Be it known that I, CHARLES PERILLAT, a citizen of France, residing in Boston, in the county of Suffolk and State of Massachusetts, have invented an Improvement in Hydrocarbon Street-Lamps, of which the following description, in connection with the accompanying drawings, is a specification, like characters on the drawings representing like parts.

This invention relates to a hydrocarbon-burning lamp especially designed for lighting streets and like places exposed to the weather.

In street-lights employing a hydrocarbon oil as the illuminant and as now commonly constructed and known to me the vaporizer is located in close proximity to the mantle within the ordinary glass globe or lantern, which is provided with suitable means by which access may be had to the said vaporizer and mantle. The globe or lantern is located at the upper end of a post, which is of such height as to require the use of a ladder in order to obtain access to the vaporizer to light the lamp with the usual torch. It frequently happens that when the door of the lantern is opened to light the lamp the mantle is shattered by the force of the wind, thereby increasing the cost of maintaining this system of lighting.

This invention has for its object to provide a street-lamp of the class referred to in which the lamp can be lighted without exposing the mantle to the wind and without the use of the ladder usually employed. For this purpose I employ a hollow post provided at its upper end with a glass globe or lantern and at its lower end with an enlarged base, which may and preferably will be made of sufficient size to contain the oil-tank and vaporizer and in general all the operative parts of the lamp except the burner and mantle, which are located in the globe at the top of the post. The hollow post contains within it means for lighting the gas or vapor as it issues from the burner within the globe at the top of the post, which means is under the control of the operator from within the hollow base of said post. Provision is made within the hollow

base, whereby the kerosene or other liquid hydrocarbon used may be prevented from freezing in extremely cold weather, as will be described. These and other features of this invention will be pointed out in the claims at the end of this specification.

Figure 1 is a partial section and elevation of a hydrocarbon street-lamp embodying this invention; and Fig. 2, a section on the line 2 2, Fig. 1, looking toward the left.

In the embodiment of the invention herein shown *a* represents the globe or lantern, which is located at the upper end of the hollow post *b*, provided with a substantially large base *c*. The post *b* and base *c* may be of metal and made in one or more parts, as desired, and the globe *a* is made of glass and is provided with a suitable cap *d*, which may be of metal.

In accordance with this invention the hollow base *c* contains within it the main operative parts of the lamp proper—namely, the oil-supply tank *e*; vaporizer *f*, connected thereto by a pipe *g*, provided with a valve *h*; a vapor-mixing chamber *i*, into which the vapor is discharged from the vaporizer and wherein said vapor is admixed with air supplied by the air-tubes *j*; a heater or burner *k*, which is connected with the mixing-chamber *i* by a pipe *l*, provided with a shut-off valve *m*. The vaporizer may be of any suitable or desired construction, but preferably that shown in United States Patent No. 654,669, granted to me July 31, 1900, it being provided with a needle-valve *n*, by which the quantity of vapor discharged into the mixing-chamber may be regulated. The mixture of vapor and air is conducted from the chamber *i* to one or more burners *o*, located within the globe *a*, and in the present instance two burners are shown, (see Fig. 2,) which are connected to the mixing-chamber *i* by a pipe *p*, extended through the hollow post and into the hollow base, wherein it may be provided with a shut-off or valve *q*.

The burners *o* may be of any suitable or usual construction and are provided with mantles *s*, such as now commonly employed with this class of lamps. As above stated, provision is made for igniting the vapor at the

burners from within the hollow post, and in the present instance I have shown one means for accomplishing this result.

In the present instance the mixing-chamber *i* has connected to it a pipe *3*, extended up into the globe *a* and provided with branches *4*, which coöperate with the burners *o*.

The pipe *3* is located adjacent to and substantially in line with the vapor-conducting pipe *p*, and the branches *4* are similarly located with relation to the burners *o*, as clearly shown in the drawings. The pipe *3* and its branches *4* are provided with a line of perforations *5* on the side adjacent to the pipe *p* and the burners *o*, so that vapor issuing from the said perforations may be ignited and the flame employed to heat the pipe *p* and also ignite the vapor at the burners. The pipe *3* may and preferably will be provided with a shut-off or valve *6*, which is accessible from within the hollow base of the lamp-post.

To facilitate an even distribution of the vapor throughout the length of the tube or pipe *3*, which latter in practice may be of considerable length, the latter may be separated into an upper and a lower chamber by a flange *7* on a tube *8*, which latter is located within the lower part of the tube *3* and is of smaller diameter than the same. The tube or pipe *3* may be made in three parts, as represented in Fig. 1. By means of the smaller tube *8* a portion of the vapor may pass directly up into the upper chamber or portion of the tube *3*.

35 The base *c* may be provided with a suitable door *9*. (Shown in its open position in Fig. 1.)

The perforated tube or pipe *3* constitutes one form of igniter, which is located within the hollow post and is accessible from within the base thereof; but I do not desire to limit my invention to the particular form shown.

When the lamp is not in use, as in the daytime, the valves *6* *g* are closed, while the valves *m* *h* may be closed or open, according to circumstances, as will be described. Assuming the valves *m* *h* closed and that it is desired to light the lamp, the operator first opens the valve *m* and heats the vaporizer by means of a hand-torch or in any other suitable or usual manner. The valve *h* is then opened, which permits the oil contained in the tank *e* under pressure to flow up into the vaporizer, wherein it is vaporized, and the needle-valve *n* having been opened the vapor passes into the mixing-chamber *i*, from which it passes through the pipe *l* into the heater or auxiliary burner *k* and from which it issues, being ignited by the hand-torch. As soon as the flame appears at the auxiliary burner the valve *6* is opened and vapor from the mixing-chamber passes into the tube or pipe *3*, from which it issues through the perforations *5* and is ignited by the hand-torch.

65 When blue flame appears in the globe or lantern *a*, the valve *g* is opened and vapor from the mixing-chamber passes up through

the tube *p* to the mantles, where it is ignited by the flame of the igniter. The valve *6* is then closed. It will thus be seen that the gas issuing from the burners and mantles located in the globe or lantern at the top of the post may be ignited from within said post, thus enabling the lamp to be lighted without the necessity of opening the globe or lantern, thereby avoiding the danger of shattering or breaking the fragile mantles by the wind, also dispensing with the use of the usual ladder now commonly employed and enabling the lamp to be lighted in a minimum time.

It is to be observed that the auxiliary burner *k* heats the interior of the hollow post while the lamp is in use, as at night, and in extremely cold weather the interior of the hollow post may be maintained sufficiently warm during the day-time to prevent the oil in the tank from freezing by opening the valves *h* *m* and regulating the needle-valve, so as to supply the auxiliary burner with a limited amount of vapor at a minimum expense, but yet sufficient in amount to keep said auxiliary burner lighted to accomplish the purpose specified.

The hollow base *e* may be provided at its upper and lower ends with air-inlet ports or openings 15 16 to admit air to support combustion, and the said openings may be protected by suitable hoods 18 19.

I claim—

1. In a lamp of the class described, the combination of a hollow elongated post, a globe or lantern at the upper end of the post and having the chamber within the globe communicating with the chamber in the post, a burner in the globe, a burner-tube extending from the chamber in the post to the burner in the globe, means for igniting the globe-burner extending from the chamber within the post to the chamber in the globe, a liquid-supplying receptacle in the post remote from the passage of communication between the post and the globe, a vaporizer, an auxiliary burner and a mixing-chamber all within the post and adapted to supply vapor to the burner within the globe, substantially as set forth.

2. In a lamp of the class described, the combination of the hollow post, the globe or lantern at the upper end of the post, the chamber of the globe communicating with the chamber in the post, the burner in the globe, the vapor-supply tube extending downwardly from the burner, the igniting device extending upward from the chamber within the post to the chamber within the globe, the opening in the lower part of the post permitting access of the igniter, whereby the operator can obtain access to the interior of the lower part of the post for igniting the burner in the globe, the oil-supply tank in the lower part of the post and the vaporizer and mixing-chamber for supplying vapor to the burner in the globe, substantially as set forth.

3. In a lamp of the class described, the

- combination of a hollow post having at the lower part an entrance into its interior chamber, the globe or lantern at the upper end, the burner in the globe, the downwardly-extending vapor-supply tube for the burner, the mixing-chamber, the vaporizer, the auxiliary vaporizer-burner, the oil-supply tank in the bottom part of the post communicating with the vaporizer, said post and globe or lantern having a passage-way from one to the other through which passage-way the lighting of the burner in the globe can be effected from the lower part of the post, substantially as set forth.
4. In a lamp of the class described, the combination with the globe or lantern, the hollow post below the globe, having an entrance through its wall, and means for closing said entrance, said post being adapted to provide a relatively large interior chamber, an elongated vapor-supply tube for the burner in the globe extending downward in the post, an oil-supply tank, a vaporizer, a mixing-chamber, and a secondary burner, all within the chamber in the post and arranged to permit the heated currents from the secondary burner to pass upward through the post around the vapor-ducts above the oil-tank to heat them without heating the tank, substantially as described.
5. In a lamp of the class described, the combination of the globe or lantern, the vapor-burner therein, the hollow post below the globe or lantern and having the reduced or stem-like upper part and the expanded lower part or base with a closed interior chamber with an entrance and a closing device for said entrance, the elongated vapor-supplying tube extending from the globe-burner down through the reduced or stem-like part of the post to the enlarged base, the mixing-chamber at the lower end of said tube, the vaporizer, the oil-tank, and the secondary burner supplied with vapor from the mixing-chamber, all located within said base and adapted to be manipulated through the entrance therein, substantially as set forth.
6. In a lamp of the class described, the combination with a hollow post provided with a globe or lantern at its upper end, of a hydro-carbon-lamp comprising a burner located in
- said globe or lantern, a vaporizer located in the lower part of said hollow post, a mixing-chamber located in said hollow post intermediate of said vaporizer and said burner and communicating with both, an auxiliary burner located within said hollow post adjacent to said vaporizer and connected with said mixing-chamber to receive vapor therefrom, and an igniter-tube connected with said mixing-chamber and extended upward to the vicinity of the burner within the said globe or lantern, substantially as described.
7. The combination with a vaporizer, a mixing-chamber communicating therewith, a burner-tube provided with a burner, and an igniter-tube communicating with said mixing-chamber and extended to near the said burner, substantially as described.
8. The combination with a vaporizer, a mixing-chamber communicating therewith, a burner-tube provided with a burner, and an igniter-tube communicating with said mixing-chamber and extended to near the said burner, and an auxiliary burner coöperating with said vaporizer and communicating with said mixing-chamber, substantially as described.
9. The combination with a vaporizer, a mixing-chamber communicating therewith, a burner-tube provided with a burner, an igniter-tube provided with gas-outlets in its side, means to separate said tube into chambers, and means to conduct vapor from one chamber to the other, substantially as described.
10. The combination with a vaporizer, a mixing-chamber communicating therewith, a burner-tube provided with a burner, an igniter-tube provided with vapor-outlets in its side, means to separate said igniter-tube into chambers, and means within said igniter-tube to conduct vapor from one chamber to the other, substantially as described.
- In testimony whereof I have signed my name to this specification in the presence of two subscribing witnesses.

CHARLES PERILLAT.
